UNITED STATES PATENT OFFICE.

SIMON W. WARDWELL, JR., OF WOONSOCKET, RHODE ISLAND.

TABLE EXTENSION-LEAF.

SPECIFICATION forming part of Letters Patent No. 340,176, dated April 20, 1886.

Application filed September 5, 1885. Serial No. 176,261. (No model.)

To all whom it may concern:

Be it known that I, SIMON W. WARDWELL, Jr., a citizen of the United States, residing at Woonsocket, in the county of Providence and 5 State of Rhode Island, have invented certain new and useful Improvements in Table Extension-Leaves, of which the following is a specification.

My invention consists of a shelf adapted for 10 application to tables, &c., composed of a series of segmental sections pivotally supported at or near the edge of the table or other platform, and so constructed and arranged that the sections may be compactly folded one within 15 the other beneath the table top or platform, while at the same time it may readily be drawn out and expanded into position and greatly increase the supporting-surface.

In the drawings, Figure 1 is an inverted 20 plan view of the folding shelf, showing it applied to the top of a table and partially drawn into position. Fig. 2 is an end view in the position shown in Fig. 1, and Fig. 3 is a perspective view of one of the shelf-sections inverted.

B represents the platform supporting the shelf—as, for instance, the top of a table of ordinary construction. To the under side of the top B or platform, near one corner, is secured, by screws or otherwise, a bracket, D, composed of a plate, a, and a downwardly-projecting arm, b, at one side of which are perforated ears c, holding a pintle or pivot-pin, d. Supported upon this bracket is the folding 35 shelf E, consisting of a number of sections, F, pivotally secured to the pin d.

Each section F is preferably made of sheet metal of such thickness as to secure the desired stiffness, and the main or body portion x thereof approximates in shape an elongated triangle or sector of a circle, and at one of its sides at right angles is a flange, z, formed by bending the body portion downward, said flange being again bent inward to form an 45 other flange or ear, y. The inner end of the ear y as well as the corresponding end of the body portion x is perforated at t to receive the pin d.

The sections F are of different sizes, so that 50 they may be compactly folded one within the other, whereby all may be brought within the compass of one of the sections, while they all

may with great facility be spread to form a circular shelf, adding materially to the size of the table or platform to which it is applied. 55

To limit the movements of the sections in respect to each other, each is provided with a lip or bent finger, f, that extends round the edge of the next adjoining section, so as to permit one to fold within the other, but strikes 60 the flange Z of said section when they are unfolded, so as to prevent entire separation. As the side flanges, Z, are formed each in one piece with the sections, they brace and stiffen 65 the sector portions and prevent sagging or yielding of the parts, thus obviating the use of heavy material.

To the under side of the top or platform B, and in close proximity to the path of movement of the shelf-sections F, is secured a curved 70 guide-rod, G, so shaped as to project slightly under the sections when folded, and upon the adjacent face of the inner section is a loop, e, receiving said rod, so that the inner end of said section is at all times supported by said 75 rod and its outward movement limited, to prevent it swinging wholly from beneath the platform. This guide-rod also affords a support for all the sections when folded.

To strengthen and stiffen the sections at the 80 outer edges I provide each with an edge bead or rib, s, formed in any suitable manner.

To retain the sections in their proper place after having been spread, I provide the outer section, F, with a ring, p, or hook, catch, or 85 other retaining device adapted to engage with a hook or staple, m, on the under side of the table, so that after spreading the shelf to its full extent the parts are firmly held in place, and the accidental folding of the shelf prevented. 90

Instead of making the shelf-sections out of sheet metal, as stated, they may be made of any other suitable material, as papier-maché, stiffened paper, veneer, &c. It is also obvious 95 that the three parts forming the sections, instead of being formed from one piece by bending, may be made separately and fastened together.

While I have shown and described my invention as applied to the corner of a platform or table, I do not wish to be limited to any such application, as it will be obvious that it may with equal facility be applied to the side, and 100

it may be used with other articles and in different positions, as with stationary shelves, wall-brackets, desks, &c., and numerous other articles of similar character where a device of this kind could be conveniently applied; and it will likewise be observed that the construction of the shelf and the parts composing it may be slightly varied, according to circumstances, without departing from the essential features of the invention.

Without limiting myself to the precise construction and arrangement of parts shown, I claim—

1. A folding shelf composed of a series of sector-shaped sections pivotally secured together at their narrow ends, and adapted to fold one within the other, substantially as and for the purpose set forth.

2. A folding shelf composed of a series of sector-shaped sections adapted to fold one within the other and pivoted at the inner ends to a vertical pivot, and stops for preventing each section from being separated from the adjacent section, substantially as and for the purpose set forth.

3. The combination, with a platform, of a shelf composed of a series of sections pivoted at their inner ends to a vertical pivot, and capable of folding one within the other, substantially as and for the purpose set forth.

4. The combination, with a platform, of a bracket secured thereto, a shelf composed of a series of sector-shaped sections pivoted at their inner ends to said bracket, said sections adapted to fold one within the other, and stops for limiting the movement of the sections, substantially as and for the purpose set forth.

5. The combination of the platform, a

bracket secured thereto at the corner, and a shelf composed of a series of sector-shaped sections pivotally supported by the bracket, and provided with stops for limiting the spread of the sections, substantially as and for the purpose set forth.

45

6. The combination of the platform, a bracket secured thereto at the corner, and a shelf composed of a series of sector-shaped sections pivotally supported by the bracket, and provided with stops for limiting the spread of the sections, and a retaining device for securing the sections when spread, substantially as and for the purpose set forth.

50

7. The combination of the platform, a bracket secured thereto, a shelf composed of a series of sector-shaped sections, each formed with a side brace and ear projecting laterally therefrom, said sections being pivoted to the bracket and adapted to fold one within the other, stops for limiting the spread of the sections, and a retaining device for securing the sections in place when spread, substantially as and for the purpose set forth.

60

8. The combination of a table or other like support, a bracket secured thereto, a shelf composed of a series of sector-shaped sections pivoted at their inner ends to the bracket and adapted to fold one within the other, stops for limiting the spread of the sections, and the guide-rod, substantially as and for the purpose set forth.

65

In testimony whereof I have signed my name to this specification in the presence of two subscribing witnesses.

SIMON W. WARDWELL, JR.
